UNITED STATES PATENT OFFICE.

HARRY GROVES AND DAVID E. LAIN, OF BELLINGHAM, WASHINGTON.

OIL-SHALE DISTILLATION APPARATUS.

Application filed February 4, 1921. Serial No. 442,312.

To all whom it may concern:

Be it known that we, HARRY GROVES, a citizen of the United States, residing at Bellingham, in the county of Whatcom and State of Washington, and DAVID E. LAIN, a citizen of the United States, residing at Bellingham, in the county of Whatcom and State of Washington, have invented a new and useful Oil-Shale Distillation Apparatus, 10 of which the following is a specification.

Our invention relates to improvements in oil-shale distillation apparatus adapted to recover from the oil shales of Colorado and Utah, by destructive distillation, the essential and lubricating oils and tars which they contain; and the objects of this invention are: to provide a retort which will have a large capacity for reducing the rock and be effective and efficient in setting free the volatile constituents of the shale, be adapted 20 for controllable and continuous movement of the shale therethrough, be adapted for mixing the fine and coarse granules of shale as they enter the retort, be adapted for mixing said granules as they pass through the retort, be provided with means to prevent the entry of air into the retort with the ore, be adapted for separate removal of the several fractions of the volatile content, be 25 adapted to cause the passage of the crushed rock through the retort in a thin stream while under the action of heat of controllable temperatures, be adapted to use a so-called noncondensing gas obtained, during the process, from said rock to heat said rock both by burning the gas and by heating it and passing it through the broken rock to mix with and carry off the products of distillation, to provide means to condense the 30 volatile products of the distillation, except said noncondensing gas, to provide for washing and purifying the noncondensing gas used in the burners, to provide for the passage of said noncondensing gas into the burners and also through the crushed rock under controllable pressures, to provide for the continuous mechanical removal of tailings from the retort, and to provide other desirable, convenient, and efficient features 35 which will more fully appear.

We attain these objects with the apparatus illustrated in the accompanying seven sheets of drawings in which Figures 1, 2 and 3, show three contiguous portions of the retort in front elevation, Fig. 4 is a plan view

of Fig. 3 in section on the bent line 4—4, Fig. 5 is a plan view of a quadrant of Fig. 1 in section on the line 5—5, Fig. 6 is the outside elevation of Fig. 5, Fig. 7 is the inside elevation of Fig. 5, Fig. 8 is a side elevation of one of the burners shown in Fig. 5 drawn on a larger scale, Fig. 9 is a plan cross section of Fig. 2 on the bent line 9—9, Fig. 10 is a plan view of the outer end of the condensing pipes, Fig. 11 is a side elevation of Fig. 10, and Fig. 12 is a plan view of the gas pump, gas washer and purifier, burning gas storage holder and heating gas storage holder, drawn on a smaller scale.

Similar characters refer to similar parts throughout. Certain parts are broken away to show others hidden thereby.

The oil shales of Colorado and Utah by destructive distillation yield products similar to those obtained from petroleum. In general: our apparatus comprises a retort which retains the rock in a thin layer as it passes therethrough, means for keeping the retort evenly full of crushed shale and mixing it as it enters, means for drawing out the tailings at a controllable rate, means for mixing the shale as it passes through the retort, means for heating it indirectly through the retort walls by burning some of the noncondensing gas won therefrom, means for heating it directly by passing superheated noncondensing gas therethrough, means for carrying off the several fractional products of distillation through separate condensing pipes and into separate receptacles, a pump for forcing the noncondensing gas through the service routes, and means for purifying that part of the noncondensing gas used in the burners.

More particularly: Four posts on which are supported the outer retort pipe or shell and the outer brick wall are marked 13. Two posts on which are supported the inner retort pipe or shell and the inner brick wall are marked 14. Four columns which support a circular structure of beams and spokes on which bear said inner retort wall and inner brick wall are marked 15. 16 is a base on which rests said columns. 17 is an I beam on posts 14 and bearing base 16. A set of I beams resting on posts 13 are marked 18 and 19. A circular hollow beam 20 rests on columns 15. A circular hollow beam 21 is concentric with beam 20, to which it is fastened by spokes 21^a, and it supports 20

the inner retort shell by mounting annular angle bar 27^a which is fastened to said shell. 22 is a circular, hollow beam which supports the outer brick wall. 23 is a hollow annular beam which mounts annular angle bar 26^b which is fastened to the outer retort shell. Beams 22 and 23 are mounted on I beams 18 and 19. 24 is an annular channel beam mounted on 22 and supporting the outer wall of brick. 25 is an annular channel beam mounted on beam 20 and supporting the inner brick wall. 26 is the outer retort shell. 26^a is the outwardly flared upper end of retort wall 26. 26^b is an annular angle beam fastened to shell 26 and bearing on beam 23. 27 is the inner retort wall. 27^a is an annular angle beam fastened to wall 27 and bearing on beam 21. 27^b is a housing flange around the fraction pipes 179-188. 28, 29 are sixteen similar annular downwardly flared baffles, each in form a truncated cone, fastened to the inside of retort wall 26. 29, 29 are sixteen annular downwardly flared baffles, each, in form a truncated cone, fastened to the outside of inner retort wall 27 and are in staggered relation with baffles 28. 30, 32, 34, 36, 38, 40, 42, 44, 46, 48, 50, 52, 54, 56, 58, 60 and 62 are annular recesses or chambers in the outer shell 26 of the retort, they are behind baffles 28 and communicate with the retort chamber through an annular slot at the bottom of said baffles. 31, 33, 35, 37, 39, 41, 43, 45, 47, 49, 51, 53, 55, 57, 59, and 61 are annular recesses or chambers in the inner shell 27 of the retort behind baffles 29. They communicate with the retort chamber through an annular slot at the bottom of baffles 29. 63 is an annular recess in wall 26 near its upper end and communicates through a narrow, annular slot with the retort chamber. 64, 64 are peripheral ridges in wall 26 at the juncture of the tops of the truncated cones which determine the form of said wall. 65, 65 are peripheral ridges at the juncture of the bases of the truncated cones which determine the form of wall 27. Wall 26 is built in five sections, with adjacent external flanges by which they are bolted together with gaskets between. Starting from the bottom these adjacent flanges are marked 66 and 67, 72 and 73, 76 and 77, and 80 and 81 respectively. Wall 27 is built in five sections also, with adjacent external flanges by which they are bolted together with gaskets between. Starting from the bottom these flanges are marked 68 and 69, 70 and 71, 74 and 75, and 78 and 79 respectively. 82 is a metal cover on top of the inner shell 27, and has an outlet into stack 82^a, closable with damper 82^b. 83 is a foot flange fastened on the lower end of inner shell 27. On it the column of ore filling the retort chamber rests. 84 is an annular flanged guide fastened to wall 26, with brackets 84^a, at its lower end to provide a slideway for doors 85. 85, 85 are vertically slideable doors in stave relation between slideway 84 and wall 26. Each door is provided with a lug at its upper end in which 70 is a tapped hole for an adjusting screw 85^a engaged therein and mounted for revolution in the flange on slideway 84. Doors 85 control the opening beneath the lower end of wall 26. 86 is a bank of gas burners which 75 together entirely encircles the retort. These burners are located in a fire box at the lower end of flue 143, and are divided into four quadrant banks, one of which is shown in Fig. 5. Each burner of the bank is provided with a gas valve 87, and an air inlet 87^a, making a Bunsen burner. 88 is a bank of gas burners located in a firebox at the bottom of flue 102. They are divided into four quadrant banks, one of which is shown 85 in Fig. 5. Each of these burners has a gas valve 89 and an air inlet pipe 89^a, making a Bunsen burner. 90 is a gas burner located in central well 102, it is provided with gas valve 91 and air inlet pipe 91^a. 92-97 are 90 six sets of quadrant gas burners located in flue 104 above bank of burners 86. One half of set 97 is shown in Fig. 4. Each quadrant burner of each of said sets is provided with one of gas valves 92^a-97^a and one of air-inlet pipes 92^b-97^b. 98 is an annular brick wall footed on beam 25 and forms the inside wall of flue 103 and the wall of well 102. 99 is a brick wall enclosing the retort and forms the outer wall of flue 104 and is footed on beam 24. 100 is a metal cover over wall 99 and flue 104. It has holes forming outlets from flue 104 which can be more or less completely closed by movable slide 101 105 slidable on said cover and having holes registerable with said holes through the cover. 102 is a central well within brick wall 98. 103 is the inner flue and is between the inner brick wall 98 and the inner retort wall 27. 104 is the outer flue and is formed by the outer retort shell 26 and the outer brick wall 99. Four nearly similar brackets, 105, are each fastened to the upper end of inner shell 27 and are connected to outer retort shell 26 in a vertically slidable joint at 106. 11 These brackets provide bearings for four bevel gears 114. 107 is a receiver for crushed shale. From it leads downward two chutes 108. The lower ends of these chutes pass through holes in two of brackets 105 and deliver ore to hopper 109. 109 is an annular revolvable hopper mounted on bevel gears 114, 116, guided by rollers 117, is concentric with and surrounds inner shell 27 and has a bottom 110, and a dependent neck 111 that registers with the cylindrical part of outer shell 26 which it nearly approaches in the flared upper end of said shell at 26^a. A number of vertical, radially spaced partitions 112 subdivide said table. 115

Said partitions pass beneath the ends of chutes 108, overhang bottom 110 and approach shell 27 quite closely. 113 is an annular disc fastened to the bottom of table 5 bottom 110 and extends outward as a flange. The lower side of its periphery is supplied with bevel gear teeth to engage with gears 114, 116, three of which, 116, are mounted as idlers on studs in brackets 105, and the 10 fourth, 114, is mounted fixed on a shaft mounted for revolution in a bearing on one of brackets 105, and to the outer end of said shaft is fixed pulley 115. A guide roller 117 is mounted for revolution on a vertical 15 stud in a lug on each of brackets 105 and bears against the cylindrical shell of table 109. 118 is an annular disk with teeth of a bevel gear on the lower side of its periphery mounted on balls on ball race 119 fastened 20 to the lower end of shell 26. Ring 120 is fastened to said shell above 118 for a top guide. 121 is a scraper fastened to annular disc 118 with standard 121^a and revolves, with said disc, close to the top surface of flange 25 83 to scrape tailings from said flange. In practice as many of these scrapers are used as desired. Two are shown in Fig. 1. 122 is a tailings receptacle below the retort large enough to catch the tailings as they are 30 scraped off of flange 83. 123 is a screw conveyor mounted for revolution in bearings in the bottom of said receptacle. 124^a is a pulley on the lower end of the conveyor shaft. 124, see Fig. 12, is a heating-gas, 35 storage holder, the greater part of which is broken away for lack of room for the illustration, supported, to hang in water tank 125, by cables over sheaves on posts. One of said cables is shown at 128, one of said 40 sheaves at 127 mounted for revolution in bearings on one of said posts 126. The posts are set up on the wall of water tank 125. The weight of said holder is partly counterbalanced by weights fastened to cables 128, one of which is shown at 129. The 45 relative weight of said gas tank and weights determines the pressure under which gas is retained in said holder. 130 is a service gas pipe from holder 124 and has valve 130^a. Through a system of pipes all marked 50 130 connections are formed to deliver heating gas from said holder to four quadrant gas heaters forming the front wall of the fire box in which operates gas burner 88. 55 Each of four pipes 130^b connects one of gas heaters 131^a with one of four quadrant gas heaters 131 which together form the front wall of the fire box in which burners 86 operate, see also Fig. 5. Each of pipes 130^b 60 through pipe 130^c delivers heating gas to annular recess 30 in the outer shell wall. 132 is a burning-gas storage holder, see Fig. 12, the greater part of which is broken away for lack of space for the illustration, 65 supported, to hang in water tank 133, by cables over sheaves on posts. One of said cables is shown at 136, one of said sheaves at 135 mounted in bearings for revolution on one of said posts 134. Said posts are set on the wall of the water tank. The 70 weight of said holder is partly counterbalanced by weights on said cables, one of which is shown at 137. The relative weight of said holder and weights determines the pressure at which gas is retained in said holder. 138 is a gas service pipe from holder 132 and has valve 138^a. Pipe 138 through a system all of the members of which are similarly marked, connects with each of 75 four quadrant gas heaters 139 which together form the back wall of the fire box for burners 86, and also connects with each of the four quadrant gas heaters 140 which together form the back wall for the fire box for burners 88, with central-well burner 90, and with each of the four quadrant burners of sets of burners 92-97. From each of the four heating gas heaters 131 rises a stand pipe 141 in flue 104. From each of pipes 141 pipe 142 connects with annular recess 32, pipe 143 with recess 34, pipe 144 with recess 36, pipe 145 with recess 38, pipe 146 with recess 40, pipe 147 with recess 42, pipe 148 with recess 44, pipe 149 with recess 46, pipe 150 with recess 48, pipe 151 with recess 50, pipe 152 with recess 52, pipe 153 with recess 54, pipe 154 with recess 56, pipe 155 with recess 58, pipe 156 with recess 60, pipe 157 with recess 62, and pipe with valve 158 with recess 63. Four pipes 31^a lead from annular recess 31 and connect with condenser pipe 173^a. Sets of four pipes 159-163 respectively lead from annular recesses 33, 35, 37, 39 and 41 and connect with condenser pipes 174-178 respectively. Pipes 164-173 respectively lead from annular recesses 43, 45, 47, 49, 51, 53, 55, 57, 59, and 61 to condenser pipes 179-188 respectively. Main noncondensing gas pipe 189 connects with the lower end of each of condenser pipes 173^a and 174-188, back of their traps 173^b and 174-188^a respectively, see Fig. 10, and leads through valve 189^a to gas pump 195, see Fig. 12, through said pump either through valve 189^b into heated gas holder 124 or through valve 189^c into gas washer 190, through said washer into pipe 191, which leads into gas purifier 192, through said purifier into pipe 193 which leads into burning gas holder 132. 194 is a water pipe 120 which through valve 194^a leads into washer 190. 195 is a gas pump in main noncondensing gas line 189 and has pulley 196 for belt connection to a prime mover not shown. 125 In operation: Properly crushed and screened oil shale is delivered to receiver 107 in sufficient quantities to maintain chutes 108 full at all times. Belts from a prime mover, not shown, continuously revolve pulleys 115, 118^b and 196 main- 120

taining operation of the revolving hopper 109, scrapers 121 and gas pump 195 each at the desired rate. The space between the hopper and the lower ends of chutes 108 is maintained full of ore, and partitions 112 as they move tend to keep the top of the retort chamber level full. At the bottom of the retort the tailings spread out beneath doors 85 on flanges 83 until they block the outlet. Then moving scrapers 121 shoves them from the flange and they are caught in the receptacle beneath whence they are carried to the dump by conveyor 123, which is revolved by a belt from a prime mover 15 on pulley 124^a. The rate of movement of the ore down through the retort chamber is determined by the height of the door opening, the number of scrapers and the rate of their movement, all of which are under control.

As the ore moves down through the retort it is somewhat mixed and loosened by being carried from side to side by the crooked course of the chamber, but it is more positively stirred by passing the ends of the conical baffles since particles leaving these pass into positions nearly in the middle of the chamber. The retort chamber is made as narrow as is compatible with free downward movement of the ore.

A supply of noncondensing gas is maintained in gas storage holders 124 and 132. Gas pump 195 is continuously operated, creating a vacuum in pipe 189 and forcing the gas therefrom into said tanks. The gas going into holder 124 is not cleaned while that reaching holder 132 has first passed through washer 190 and purifier 192 where it is cleansed. This clean gas is supplied to burners 86, 88, 90 and 92-97 under the desired pressure. The gas burning at burners 86 and 88 heats gas heaters 131, 131^a, 139 and 140 and heats both walls of the retort. The effectiveness of the gas burned in said burners is increased by the heat received in passing through heaters 139 and 140.

Burner 90 maintains the temperature in central well 102 sufficiently to prevent condensation in the products' pipes passing therethrough. Burners 92-97 reinforce burners 86 in heating the outer shell of the retort and aid in localizing temperatures. As shown, the means for heating the contents of the retort indirectly can be varied, at will, both as to temperatures and distribution thereof. The amount of air served the burners is controllable by the shutters at the entrance of the air inlets. If desired, air for the burners can be supplied through a single system of pipes under pressure.

Uncleaned, noncondensing gas, for the purposes of this description called heating gas, is supplied by holder 124, under any desired pressure, to heaters 131 and 13

where it is superheated and from where it passes into the annular recesses in the outer shell. From them it passes through the shale in the retort chamber, heating the same and carrying off with it the products of the distillation, being set free, into the annular recesses in the inner shell and from there into the several condenser pipes. In these pipes the heater gas and the noncondensable part of the products remain gaseous and pass through the gas pump either into tank 124 or 132 as desired. The condensable portions of said products enter the traps at the condenser pipes' ends and are drawn off at said pipes' ends into the several receptacles prepared for the several fractions of said products of distillation.

The character of the product passing from said condensers is kept under constant observation, and on it depends the several adjustments in the apparatus and operation thereof that may affect said character. It is now understood that the segregation of the products' outlets in the retort shell and the easy control of temperatures at those outlets make fractioning of said products in our apparatus easily possible.

Heating gas forced through valves 158 near the top of the retort fills the voids in the ore mass as it enters said retort and prevents air from passing down into the retort chamber with the ore. Enough gas is admitted through said valves to be barely noticeable at the flared end 26^a of the outer shell.

During cold weather air cooling is ordinarily sufficient for the condenser pipes. But, owing to the quantity of noncondensing gas used for heating, in the warm weather the condensing pipes are passed through brine maintained at a low temperature by refrigerating pipes therein in the well known manner.

Washer 190 and purifier 192 are well known devices used in the manufacture of gas prepared for domestic lighting and heating and require no detailed disclosures.

Having thus fully disclosed our invention, what we claim as new and desire to secure by Letters Patent is.—

1. In combination, an inner, vertical retort shell having a plurality of gas chambers, an outer, vertical retort shell having a plurality of gas chambers facing said chambers in said inner shell, means for heating one of said retort shells, conduits leading from each of said gas chambers in said heated shell to a gas supply, conduits leading from each of said gas chambers in said other shell to a condenser, and means whereby gas is caused to flow from said gas supply into said hot-shell gas chambers transversely through and between broken shale between said inner and outer retort shells, into said gas chamber in said

other retort shell and thence into said condenser pipes.

2. In combination, an inner, vertical retort shell having a plurality of annular grooves in its outer wall; an outer, vertical retort shell, concentric with said inner shell, having a plurality of annular grooves in its inner wall facing said grooves in said inner shell and in staggered relation therewith; a downwardly-flaring, annular baffle fastened to each of said shell walls above each of said annular grooves to be in front of the same; means to heat one of said retort shells; conduit connections between each of the grooves in said heated shell to a source of gas supply; and conduit connections from each of said grooves in said other shell to a condenser.

3. In combination, a vertical retort comprising an inner and an outer shell, means adapted to support said shells in concentric relation, a revolvable annular hopper mounted for revolution on top of said retort having a hollow cylindrical outlet projecting within said retort concentric with and spaced from said inner shell, a plurality of radial, vertical blades fixed in said hopper with their inner ends projecting over said hopper outlet to juxtaposition with said inner shell, means to revolve said hopper, means adapted to heat one of said retort shells, and means whereby hot gas is caused to flow through openings in the walls of said heated shell, transversely through and among broken shale in said retort and to and through openings in the other retort shell.

4. In combination, a vertical retort comprising an inner and an outer shell, an exterior flange fixed on the lower end of said inner shell extending beyond said outer shell, means adapted to support said shells in concentric relation with the lower end of said outer shell spaced above said flange, a plurality of gates mounted for vertical movement on the lower end of said outer shell as an extension of the same above said flange, a plurality of scrapers mounted for revolution around the vertical axis of said outer shell over the upper surface of said flange, means to revolve said scrapers, means to maintain said retort full of broken shale, and means whereby hot gas is caused to flow through openings in the walls of said shell, into and among and transversely through broken shale in said retort and to and through openings in said other retort shell.

5. In a retort comprising two, circular, concentric, vertical shells with an intervening retort chamber, the combination of said retort shells; a plurality of pipes connected

to said inner shell leading from said chamber; a plurality of pipes connected to said outer shell leading into said chamber, said pipes connected to said chamber at vertically spaced locations in staggered relation; and means whereby hot gas is caused to flow through said pipes connected to one shell transversely through said retort chamber and among broken shale therein and into and through said pipes connected to said other shell.

6. In a retort the combination of an inner retort wall comprising a series of hollow truncated cones joined alternately top to top and base to base with an annular groove at the junction of each pair of said bases and having an annular baffle pendant in front of said groove as a continuation of said upper of said pair of cones; an outer retort wall comprising a series of hollow truncated cones joined in pairs alternately top to top and base to base, said retort chamber being of substantially zigzag, vertical cross section, said outer wall having an annular groove at the junction of each pair of the tops of said truncated cones and having an annular baffle pendant in front of said groove, which is an extension of the walls of said upper of the pair of said truncated cones; and conduit connections from each of said annular grooves.

7. In combination, a vertical retort comprising an inner and an outer shell, means adapted to support said shells in concentric relation; a revolvable annular hopper mounted for revolution on top of said retort and having a hollow cylindrical outlet projecting within said retort, concentric with and spaced from said inner shell, a plurality of radial blades fixed vertically in said hopper with their inner ends projecting over said hopper outlet to juxtaposition with said inner retort shell, and means adapted to revolve said hopper.

8. In combination, a vertical retort comprising an inner and an outer shell, an exterior flange fixed on the lower end of said inner shell extending beyond said outer shell, means adapted to support said shells in concentric relation with an intervening retort chamber and with the lower end of said outer shell spaced above said flange, a plurality of gates mounted for vertical movement on the lower end of said outer shell as an extension of the same above said flange, a plurality of scrapers mounted for revolution around the vertical axis of said retort over the upper surface of said flange, and means to revolve said scrapers.

HARRY GROVES.
DAVID E. LAIN.
